CAN HOLDING, OPENING, AND POURING DEVICE

Russell L. Stoecker, Santa Ana, Calif.

Application July 18, 1949, Serial No. 105,321

3 Claims. (Cl. 222—86)

1

This invention relates to a device for receiving a conventional sealed liquid-containing can, opening the same whereby the contents thereof may be poured, and controlling pouring of said contents.

An object of the present invention is to provide a device of the character indicated that so conceals a liquid-containing can that the appearance thereof is enhanced for use on the table.

Another object of the invention is to provide a novel container whereby a conventional can is readily introduced therewith so that the top of said can is automatically pierced for pouring of the contents.

A further object of the invention is to provide novel combined piercing and pouring-valve control means that renders the operation efficient, safe and sanitary.

By means of the present invention, jagged edges on a can, when opened, are safely concealed; the contents remain sealed until pouring is desired to obviate drying of the can contents as may be caused by evaporation; loss of the contents is eliminated since no transfer of said contents is made to another container, such as a pitcher; etc.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a plan view of a can holding, opening, and pouring device according to the present invention.

Fig. 2 is a vertical sectional view thereof as taken on line 2—2 of Fig. 1.

Fig. 3 is an enlarged cross-sectional view on line 3—3 of Fig. 2.

The device that is illustrated comprises, generally, a container 5 provided with a handle 6 and adapted to receive a conventional can 7 containing evaporated or condensed milk, etc., and valve-controlled means 8 extending across the top of container 5 for piercing and thereby opening

2

can 7 when the same is introduced into said container.

The container 5 comprises a main body portion 9, is cylindrical and may be outwardly bulged as shown. While portion 5 is shown with an open top, the same may be closed, if desired, such closure extending to the means 8 and, thereby, concealing can 7 from the top. A bottom closure portion 10 is connected to portion 9 as by a hinge 11 at one side and a snap latch 12 at the opposite side. The two portions 9 and 10 constitute a receptacle for housing can 7. Since the diameter of can 7 is a variable, the same is centered in the receptacle as by leaf springs 13 that extend from the inner wall of body portion 9 toward the center of the same. For exerting resilient pressure against the bottom of can 7, closure 10 is provided with a resilient cushion 14 or with its equivalent, such as a spring.

20 The handle 6 is generally conventional except that the same is hollow, at least in its upper part, for reasons later apparent.

The means 8 comprises a guide bar 15 affixed to the top of body part 9 and extending thereacross. In spaced relation, so as to pierce through diametrically opposite points of the top 16 of can 7, bar 15 has two tubular projections 17 and 18, each having an angular bottom edge 19 which terminates in a sharp point 20. Around each tube 17 and 18 there is provided a sealing washer 21 which seals against can top 16 around the pierced holes 22 formed in said can top.

The guide bar 15 is provided with opposed longitudinal ways 23 for a slide 24 that is longitudinally movable. Said slide terminates, at one end, in a pouring lip 25 that is opposite to handle 6 and, at the other end, in an extension 26 that is superimposed on top of handle 6. A thumb or finger piece or button 27 is provided on slide extension 26. Spaced according to tubes 17 and 18, slide 24 is formed with holes 28 and 29 adapted to be respectively registered with said tubes 17 and 18 by projecting slide 24 relative to guide bar 15.

45 Normally, slide 24 is held retracted by a spring 30 which resides in the mentioned hollow of the handle, one end 31 of said spring being engaged with or affixed to body part 9 and the other end 32 being engaged with a projection 33 on the slide extension 26. This projection extends into the hollow of the handle through a suitable opening 34.

In use, the closure portion 10 is swung open on its hinge 11 so that a can 7 may be introduced 50 into container 5 until the sharp points 20 of

tubes 17 and 18 encounter can top 16. Then, by pressing against the bottom of can 7 and, in the opposite direction, on the means 8, said points 20 will pierce the can top and communicate the interior of the can with said tubes. The closure 10 is then swung to closed position and latched, the cushion 14 thereof serving to press the can 7 in a direction toward bar 15. This pressure will compress washers 21 so that they become effective seals. Since spring 32 holds slide 24 retracted and thereby holds holes 28 and 29 out of register with tubes 17 and 18, respectively, the fluid contents of can 7 are sealed from atmosphere and said contents are protected against contaminating dust, etc. Also, evaporation is minimized.

When it is desired to pour from the can, the handle 6 is grasped and the thumb engaged with button 27 to project slide 24 and bring holes 28 and 29 into respective register with tubes 17 and 18. Now, when the container 5 is tilted forward, the contents of can 7 will pour through tube 17 and onto and off pouring lip 25, tube 18 and hole 29 serving as a vent to the interior of can 7. By releasing button 27, spring 32 is immediately effective to restore the slide to retracted position sealing the can.

It will be noted that spillage is obviated even when the container is upset since slide 24 is an effective seal for the can contents, and that the objects of the invention have been fulfilled in the disclosed embodiment.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described the invention, what is claimed and desired to be secured by Letters Patent is:

1. A device of the character described comprising a container for a liquid-containing can, said container having a hinged bottom affording access for inserting the can in a direction toward the top of the container, resilient means carried by the hinged bottom for pressing the can upward in the container, a laterally directed handle on the container, there being a guideway extending across the top of the container, two spaced and sharp-ended tubes projecting downwardly from the top of the container and in communication with said guideway, said tubes being adapted to pierce the top of the can and communicate with the interior thereof when the latter is inserted into the container, a slide on said guideway and having an extension superimposed on the top of the handle, said slide having a finger-engageable member on said extension for moving the slide in the slideway, the slide having spaced holes, a pouring lip on the slide on the end thereof opposite to said extension; and resilient means housed in the handle for holding the slide retracted and the holes thereof out of register with the tubes on the guide bar, said slide being adapted to be projected to register said holes with the tubes and to project said pouring lip laterally beyond the container, whereby the contents of the can are

adapted to be poured through one of said tubes and its registered hole and off the end of the pouring lip.

2. In a can-holding device, a container for a liquid-containing can, a handle extending laterally from the container and having a hollow portion adjacent the upper part of the container, a guide bar extending across the top of the container and aligned with the hollow portion of the handle, spaced sharp-ended tubes projecting downward from the guide bar and adapted to pierce the top of said can and communicate with the interior thereof, a slide guided by the guide bar and having holes spaced according to the spacing of the tubes, a pouring lip provided on one end of the slide, spring means residing in the hollow part of the handle and engaged with the slide to hold the same and the lip thereon retracted and the holes therein out of register with the tubes, and a finger-piece on said slide for effecting projection of the latter and its pouring lip to compress said spring means and to register said holes and tubes for pouring of the can contents through one hole of the slide and onto the portion of the slide between said latter hole and the pouring lip.

3. In a device of the character described, an open-topped container having a hollow lateral handle, a member constituting a guideway and bridging across said open top, the upper portion of the handle being aligned with the guideway and constituting an extension of said guideway, two spaced and sharp-ended tubes extending downward from the guideway and adapted to pierce the top of a liquid-containing can positioned in the container, a slide operable in the slideway and provided with a finger-engageable member on the end thereof extending over the handle and with a pouring lip on the opposite end, a projection on the slide extending into the hollow of the handle, a spring in the hollow of said handle and engaged between an adjacent portion of the container and said projection to hold said slide retracted and the pouring lip thereon immediately adjacent the side of the container opposite the handle, there being holes in the slide spaced according to the spacing of the can-piercing tubes, said holes in the retracted position of the slide being out of register with said tubes and the slide, thereby, sealing the contents of the can, said slide being projectable by a finger of the hand gripping the handle and engaging said finger-engageable member to register the tubes and the holes in the slide so that, upon forward tipping of the container, the contents of the can are poured out of the hole adjacent the pouring lip, over the slide and off the end of said pouring lip.
